(57) **CLAIM**

The ornamental design for a clothes hanger, as shown and described.

DESCRIPTION

FIG. 1 is a perspective view of a cloth hanger with a metal wire hook showing one side of the hanger, and, FIG. 2 is a perspective view of the cloth hanger showing the opposite side of the hanger.

The hanger is intended to be supported on the hand supports provided in many cars above the door frames. The wire hook can be rotated about the hanger body so that it extends inwardly for easy storage of the hanger.
